DESIGN FOR A LIGHTER

Walter E. Keene, Baltimore, Md.

Application February 24, 1945, Serial No. 118,121

Term of patent 7 years

(Cl. D48—27)

To all whom it may concern:

Be it known that I, Walter E. Keene, a citizen of the United States, residing at Baltimore, in the State of Maryland, have invented a new, original, and ornamental Design for a Lighter, of which the following is a specification, reference being had to the accompanying drawing, forming a part thereof.

I claim:

The ornamental design for a lighter, substantially as shown.

WALTER E. KEENE.
